UNITED STATES PATENT OFFICE.

WILLIAM E. MARTIN, OF STAMFORD, ENGLAND.

CARBURETER.

1,115,951.

Specification of Letters Patent.

Patented Nov. 3, 1914.

Application filed April 17, 1914. Serial No. 832,528.

To all whom it may concern.

Be it known that I, WILLIAM EDWARD MARTIN, a subject of the King of Great Britain, residing at Stamford, in the county of Lincoln, England, have invented certain new and useful Improvements in Carbureters for Internal-Combustion Engines, of which the following is a specification.

The present invention is an improvement 10 in or modification of the invention for which I obtained Letters Patent in the United States of America No. 1038921.

The objects of the present invention are to produce a carbureter which will give 15 better results, which is quieter in work, and which may be automatic in action.

In the former construction the air shutter and throttle were both located in the mixing chamber, which had an air inlet direct 20 from the atmosphere.

According to the present invention I employ a separate air intake which is circular in cross section and is arranged below the mixing chamber.

25 The air intake communicates with the mixing chamber by means of a long slot or air opening. In the mixing chamber is located the sliding throttle which uncovers part of the jet opening and part of the air opening, as in the former construction.

In the air intake is located an air shutter which fits the interior of the air intake and has a slot corresponding with the air opening into the mixing chamber. The air 35 shutter is open at one end to receive air and is closed at its other end.

The invention is illustrated in the accompanying drawings, in which:—

Figure 1 is a plan of the complete automatic carbureter. Fig. 2 is a vertical section on the line 2—2 of Fig. 1, and Fig. 3 is a vertical section on the line 3—3 of Fig. 1, the arrows indicating the direction in which the sections are seen. Fig. 4 is 40 a vertical section of a modification taken through the mixing and suction chambers, showing a hand-controlled carbureter.

45 *a* is the float feed chamber, *b* the fuel slot, and *c* the eccentric pin for regulating the supply of fuel from the float feed chamber to the slot *b*.

50 *d* is the mixing chamber, in the side of which is formed the slot *b*, *e* is the sliding throttle located in the mixing chamber, *f* is the induction pipe communicating with

the mixing chamber, and *f'* is an ordinary butterfly throttle.

According to the present invention I employ a separate air intake *g*, open at one end, and which is circular in cross section, 60 and is arranged below the mixing chamber *d*. The air intake *g* communicates with the mixing chamber *d* by means of a long slot or air opening *g'*. The sliding throttle *e* simultaneously uncovers part of the fuel 65 jet *b* and part of the air slot *g'*, as in the former construction.

In the air intake *g* is located the oscillating shutter *h*, which fits the interior of the intake *g* and has a slot *h'* corresponding to 70 the air slot *g'*. The air shutter *h* is open at one end and is closed at the other or inner end, which latter is provided with a spindle *h*² passing through a hollow screw *h*³ which screws into the closed end of the air intake *g*. 75 The spindle *h*² is provided with a lever *h*⁴ by means of which it may be oscillated or rotated to regulate the passage of air through the air slot *g'*.

The screw *h*³ is adjusted to regulate the 80 longitudinal position of the air shutter *h*, so that the passage through the slot *g'* may be slightly greater or slightly less than the passage *d'* between the mixing chamber *d* and the induction tube *f*. By these means a suitable 85 mixture is provided when the throttle *e* is only slightly open. This mixture may be a rich mixture or a weak mixture, according to the position of the screw *h*³.

The air shutter *h* is preferably provided 90 with a circumferential slot *h*⁵ working over the end of a screw *g*², so that its rotary motion is limited.

When it is desired to operate the throttle *e* automatically, I provide it with a central 95 rod *e'*, which passes through one end of the mixing chamber *d*, and carries an operating piston *e*² at its end which is located within a cylinder *i* having a closed end *i'*. A passage *i*² is arranged between the induction 100 pipe *f* and the said cylinder *i*, so that as the speed of the engine increases, the suction on the said operating piston *e*² causes the throttle *e* to uncover the jet *b* and air opening *g'*, according to the requirements of the engine. 105 The operating piston is moved in the opposite direction by means of a coiled spring *e*³, the strength of which regulates the depression in the cylinder or suction chamber *i*. The end *i'* of this cylinder *i* is provided 110

with a small air hole i^3 , which is covered on the inside by a light flat brass spring i^4 , which allows air to enter readily when the piston e^2 moves in the one direction, and 5 which closes the hole i^3 on the return motion of the piston e^2 and cushions it by means of the air retained in the cylinder. The air trapped behind the piston e^2 leaks steadily past the piston which is not an air-tight fit 10 in the cylinder. Air also leaks through the joint between the end i' and the cylinder i . An ordinary butterfly throttle f' is employed in the induction pipe f , by means of which the suction on the automatic operating 15 piston e^2 may be regulated.

In order to insure that a proper flow of air takes place past the jet b , the passage through the mixing chamber d is approximately equal to the passage through the slot 20 d' , between the top of the mixing chamber d and the induction pipe f . The passage through the mixing chamber d may be regulated by making the central rod e' of the automatic throttle e of the requisite cross 25 sectional area to leave the desired passage in the mixing chamber d .

In the hand controlled carburetor shown in Fig. 4, the throttle e slides over a central rod E , which is made to the required cross 30 sectional area to produce the desired area in the mixing chamber d .

E' is a bar fixed to the sliding throttle e , by means of which the throttle e may be controlled by hand by any usual or convenient 35 mechanism.

What I claim is:

1. In a carburetor for internal combustion engines, the combination of a mixing chamber in the side of which is formed a fuel 40 slot; a sliding throttle in said chamber, a separate air intake of circular cross section located below the mixing chamber and communicating with the mixing chamber by means of a slot, a shutter fitting the interior 45 of the air intake and having a slot corresponding with the slot connecting the air intake and mixing chamber, and means for oscillating the said shutter to regulate the passage of air into the mixing chamber, substantially as set forth.

2. In a carburetor for internal combustion engines, the combination of a mixing chamber in the side of which is formed a fuel slot, means for regulating the passage of the 55 fuel to said slot, a sliding throttle in said chamber, a separate air intake of circular cross section located below the mixing chamber and communicating with the mixing chamber by means of a slot, a shutter fitting the interior 60 of the air intake and having a slot corresponding with the slot connecting the air intake and mixing chamber, and means for oscillating the said shutter to regulate the passage of air into the mixing chamber, substantially as set forth.

3. In a carburetor for internal combustion engines, the combination of a mixing chamber in the side of which is formed a fuel slot, a sliding throttle in said chamber, a separate air intake of circular cross section 70 located below the mixing chamber and communicating with the mixing chamber by means of a slot, a shutter fitting the interior of the air intake and having a slot corresponding with the slot connecting the air intake and mixing chamber, means for oscillating the said shutter to regulate the passage of air into the mixing chamber, and a screw screwing into the closed end of the air intake to regulate the longitudinal position of the said shutter, substantially as set forth.

4. In a carburetor for internal combustion engines, the combination of a mixing chamber in the side of which is formed a fuel slot, an eccentric pin adjacent to said slot to regulate the passage of fuel to said slot, a sliding throttle in said chamber, a separate air intake of circular cross section located below the mixing chamber and communicating with the mixing chamber by means of a slot, a shutter fitting the interior of the air intake and having a slot corresponding with the slot connecting the air intake and mixing chamber, and means for oscillating the said shutter to regulate the passage of air into the mixing chamber, substantially as set forth.

5. In a carburetor for internal combustion engines, the combination of a mixing chamber in the side of which is formed a fuel slot, a sliding throttle in said chamber, a rod connected to said throttle, a piston carried by said rod, a cylinder having a closed end in which said piston is located, an induction pipe, a passage connecting the cylinder with the induction pipe, a spring in said cylinder acting against the said piston, a separate air intake of circular cross section located below the mixing chamber and communicating with the mixing chamber by means of a slot, a shutter fitting the interior of the air intake and having a slot corresponding with the slot connecting the air intake and mixing chamber, and means for oscillating the said shutter to regulate the passage of air into the mixing chamber, substantially as set forth.

6. In a carburetor for internal combustion engines, the combination of a mixing chamber in the side of which is formed a fuel slot, a sliding throttle in said chamber, a rod connected to said throttle, a piston carried by said rod, a cylinder having a closed end in which said piston is located, a small air hole in the end of said cylinder, a light flat spring within the cylinder covering the said air hole, an induction pipe, a passage connecting the cylinder with the induction pipe, a spring in said cylinder acting against the

5 said piston, a separate air intake of circular cross section located below the mixing chamber and communicating with the mixing chamber by means of a slot, a shutter fitting 5 the interior of the air intake and having a slot corresponding with the slot connecting the air intake and mixing chamber, and means for oscillating the said shutter to regulate the passage of air into the mixing 10 chamber, substantially as set forth.

7. In a carbureter for internal combustion engines, the combination of a float feed chamber, a mixing chamber having a fuel slot in the side thereof, an eccentric pin for regulating the supply of fuel to the fuel slot, a sliding throttle in the mixing chamber, an induction pipe communicating with the mixing chamber, another throttle in said induction pipe, a cylinder, a passage connecting said cylinder with the induction pipe, an air hole in the end of said cylinder, a flat spring within said cylinder covering said air hole, a spring-pressed piston in said cylinder connected to the sliding throttle in the mixing chamber, a separate air intake of circular cross section below the mixing chamber and communicating therewith by means of a slot, an oscillating shutter fitting said air intake, means for oscillating said shutter, a screw screwing into the closed end 25 of the air intake to regulate the longitudinal position of said shutter, a circumferential slot in said shutter, and a screw passing through the air intake over the inner end of which works the said circumferential slot, substantially as set forth.

8. In a carbureter for internal combustion

engines, the combination of a float feed chamber, a mixing chamber having a fuel slot in the side thereof, an eccentric pin for regulating the supply of fuel to the fuel slot, a sliding throttle in the mixing chamber, an induction pipe communicating with the mixing chamber, another throttle in said induction pipe, a cylinder, a passage connecting said cylinder with the induction pipe, an air hole in the end of said cylinder, a flat spring within said cylinder covering said air hole, a spring-pressed piston in said cylinder connected to the sliding throttle in the mixing chamber, a separate air intake of circular cross section below the mixing chamber and communicating therewith by means of a slot, an oscillating shutter fitting said air intake, means for oscillating said shutter, a screw screwing into the closed end 45 of the air intake to regulate the longitudinal position of said shutter, a circumferential slot in said shutter, and a screw passing through the air intake over the inner end of which works the said circumferential slot, substantially as set forth.

In witness whereof I have hereunto set my hand in the presence of two witnesses.

WILLIAM E. MARTIN.
